CLAIM

The ornamental design for a luminaire, as shown and described.

DESCRIPTION

FIG. 1 is a bottom, front, right perspective view of a luminaire, showing our new design; the bottom, front, left perspective view being a mirror image thereof; and, FIG. 2 is a bottom plan view thereof.

The luminaire is shown recessed in a ceiling, the ceiling being shown in jagged broken lines illustrates environment only and form no part of the claimed design. The luminaire is shown with symbolic break lines along its width. The

(Continued)

appearance of any portion of the luminaire between the break lines forms no part of the claimed design.
